INCASED DRAIN PLUG

Roy S. Stephenson, San Francisco, Calif.

Application November 5, 1945, Serial No. 626,668

1 Claim. (Cl. 222—522)

1

The invention relates to a drain faucet or plug for containers and more especially to an encased extensible drain faucet or plug for shipping barrels, drums or other containers for fluids.

The primary object of the invention is the provision of a faucet or plug of this character, wherein in the same is attachable to a container having fluid content, to become a permanent part of such container, and remains with the latter at all times, and is adaptable to be encased therein so that such faucet or plug will not become damaged when the container is to be shipped from one locality to another, and will be handy for use in dispensing the content from the container when this be required.

Another object of the invention is the provision of a faucet or plug of this character, wherein leakage of the content of the container is avoided, and the necessity of inserting a drain-off device therein is entirely eliminated, the faucet or plug being applicable to all kinds of containers for holding fluids, and is novel and unique in the makeup of the same.

A further object of the invention is the provision of a faucet or plug of this character, wherein a wrench or other tool is not required for the adjustment thereof, in that such faucet or plug is permanently equipped with the necessary turning medium for the operation thereof at any and all times.

A still further object of the invention is the provision of a faucet or plug of this character, which is simple in construction, thoroughly reliable and efficient in operation, readily and easily manipulated, strong, durable, easy of application, and inexpensive to manufacture and install.

With these and other objects in view the invention consists in the features of construction, combination and arrangement of parts as will be hereinafter more fully described, illustrated in the accompanying drawings, which disclose the preferred embodiment of the invention, and pointed out in the claim hereunto appended.

In the accompanying drawings:

Figure 1 is a fragmentary sectional view through a container showing the faucet or plug constructed in accordance with the invention installed and in normal encased position.

Figure 2 is an outside face view thereof, the operating medium being partly broken away.

Figure 3 is a view of the faucet or plug looking toward its inner end, and a portion partly broken away.

Figure 4 is a sectional view taken on the line

2

4—4 of Figure 2 looking in the direction of the arrows.

Figure 5 is a sectional view taken on the line 5—5 of Figure 2 looking in the direction of the arrows.

Similar reference characters indicate corresponding parts throughout the several views in the drawings.

Referring to the drawings in detail, A designates generally a portion of a container for holding a fluid to be dispensed therefrom, and may be of any type, and is formed with an apertured lug portion 10 internally threaded, the aperture being for filling and draining the container, as usual.

15 Adapted to fit the lug portion 10 is the faucet or plug denoted at B, which constitutes the present invention and is hereinafter fully described.

This faucet or plug B, comprises a straight tube or cylindrical body 11 open at one end and permanently closed by a head 12 at the other end, while throughout the extent of the said tube or body 11 are screw threads 13 matching the threads of the lug portion 10, so that the open end of the tube or body can be engaged therewith. By 20 adjustment of the tube or body 11 in the lug portion 10 it can be worked inwardly or outwardly of the container A.

The tube or body 11 at the inner or open end thereof is internally threaded for a distance as at 25 14 for the engagement therein of a centrally perforated valve seat 15, its perforation 16 being closed by a valve 17 having the stem 18 thereof adjustably threaded at 19 through a central boss 20 formed on the inner side of the head 12 to project outwardly of the latter. When the valve 25 17 becomes unseated it clears the perforation 16 so that fluid from the container A can flow into the tube or body 11 to find way to a drain hole 21 in the said tube or body, which when worked outwardly of the container will permit the dispensing of the content thereof, as appears in Figure 4 of the drawings.

The body or tube 11 carries a hand adjusted locking collar or nut 22 which is adapted to be tightened against a gasket 23 which encircles the said tube or body and is normally compressed against the head 12 to prevent leakage at the point of junction of the tube or body with the latter, the collar or nut being loosened when it is desired to encase the faucet or plug or to extend the same from the container A, these two positions being shown in Figures 1, 4 and 5 of the drawings.

Formed on the outer face of the head 12 at 55 diametrically opposite points thereof are dove-

detailed keys 24 which are adapted for wedging engagement in a dovetailed key-way 25 provided longitudinally in a tubular detachable turning handle 26, and this key-way 25 extends only through one end of the handle, so that it can be detached for giving access to a cross-grip at the outer end of the stem 18 whereby the valve 17 may be manually opened or closed at the seat 15. The handle 26 is for manually turning the tube or body 11 to encase the same or extend it as before stated.

The handle 26 at the key-way end has telescopically fitted thereon a combined latching medium and hand-hold 27 which is of tubular form having spring tensioned finger released latches 28 engageable in keeper openings 29 in the handle 26. The hand-hold 27 when in the position shown in Figure 1 of the drawings maintains the said handle fast on the head 12. Such hand-hold when in the position shown in Figure 4 effects a cranking knob for the convenient removal of the handle from the head 12 to give free access to cross-grip at the outer end of the stem 18 of the valve 17 for the opening and closing thereof. This hand-hold 27 is swingable at right angles to the handle 26 to permit the detachment of the latter from the head 12, this position being shown by dotted lines in Figure 4 of the drawings.

What is claimed is:

In combination, a container having a threaded opening and a faucet therefor, said faucet comprising an externally threaded tubular member adjustably mounted in said threaded opening whereby the member can be screwed into and out of said container, a flanged head closing one end of said tubular member, a valve seat in the opposite end of said tubular member, a valve adapted to seat on said valve seat, a valve stem attached to said valve and threadedly engaging said head and extending there-beyond, a cross member secured to said valve stem for manually turning said valve stem to control the flow of contents from said container into said tube, a drain-hole in the wall of said tube for draining off the contents therein, a pair of diametrically posi-

tioned wedge-shaped keys on said flanged head, a tubular turning handle having a wedge-shaped keyway detachably receiving said keys and having a first and a second pair of aligned apertures, said pairs of apertures being longitudinally spaced on said tubular turning handle, a tubular latching member slidably mounted on said tubular turning handle, extensions integrally formed with said tubular latching member, aligned spring-pressed pivot pins slidably mounted in said extensions and adapted to be selectively engaged in either of said pairs of aligned apertures for selectively positioning said tubular latching member in either of one of two positions relative to said tubular turning handle whereby when said pair of pivot pins is positioned in said first pair of apertures, said tubular latching member is telescoped upon said tubular turning handle locking the same to said flanged head and when said pair of aligned pivot pins is positioned in said second pair of apertures said tubular latching member is extended beyond said tubular turning handle for pivotal movement to the same, forming a crank portion therefor, and a lock nut on said externally-threaded tubular member and adapted to be screwed thereon into engagement with the container to lock said tubular member against rotation relative to the container.

ROY S. STEPHENSON.
